CLAIM

The ornamental design for a bottle, as shown and described.

DESCRIPTION

FIG. 1 is a perspective view of a bottle showing our new design;

FIG. 2 is a front elevational view thereof, the rear elevational view being a mirror image of this figure;

FIG. 3 is a side elevational view thereof as seen from the right side of FIG. 2;

FIG. 4 is a side elevational view thereof as seen from the left side of FIG. 2;

FIG. 5 is a top plan view thereof;

FIG. 6 is a bottom plan view thereof; and,

FIG. 7 is a perspective view thereof.

The broken line showing of a spray attachment in FIG. 7 is for illustrative purposes only and does not form part of the claimed design.
